UNITED STATES PATENT OFFICE

107,440

DESIGN FOR A COMBINED ASHTRAY AND CIGARETTE EXTINGUISHING DEVICE

John Thomas McCreary, Chicago, Ill.

Application May 6, 1937, Serial No. 69,208

Term of patent 7 years

To all whom it may concern:

Be it known that I, John Thomas McCreary, a citizen of the United States, residing at Chicago, in the county of Cook and State of Illinois, have invented a new, original, and ornamental Design for a Combined Ashtray and Cigarette Extinguishing Device, of which the following is a specification, reference being had to the accompanying drawing, forming part thereof.

Figure 1 is a perspective view of a combined ashtray and cigarette extinguishing device showing my new design; and Fig. 2 is a plan view of the same.

I claim:

The ornamental design for a combined ashtray and cigarette extinguishing device, as shown.

J. THOMAS McCREARY.
